2 SHEETS—SHEET 2.

UNITED STATES PATENT OFFICE.

GEORGE E. FRAZIER, OF MUNCIE, INDIANA, ASSIGNOR OF TWO-FIFTHS TO ROBERT LEO FELL, OF MUNCIE, INDIANA.

SAFETY STOP FOR TRAINS.

1,410,744.

Specification of Letters Patent. Patented Mar. 28, 1922.

Application filed August 18, 1921. Serial No. 493,397.

To all whom it may concern:

Be it known that I, GEORGE E. FRAZIER, a citizen of the United States, residing at Muncie, in the county of Delaware and State 5 of Indiana, have invented new and useful Improvements in Safety Stops for Trains, of which the following is a specification.

The object of this invention is to provide means to automatically stop railway trains 10 provided with an air-brake system, by setting the brakes, to prevent collisions between trains moving on the same track or between trains moving on tracks that cross each other.

15 A further object is to provide a mechanism that may be easily and inexpensively applied to brake systems already in common use, and which may likewise be applied to and worked in conjunction with the semaphore devices now usually employed.

I accomplish the above and other objects which will hereinafter appear, by the mechanism illustrated in the accompanying drawings, in which—

25 Fig. 1, is a vertical section through the cab of a locomotive steam engine with my brake control invention applied, on the line 1—1 of Fig. 2, except that the semaphore is at the left of the engine instead of to 30 the right as in Fig. 2. Fig. 2 is a cross section on the line 2—2 of Fig. 1, but with the semaphore located to the right of the engine, to illustrate the range of adaptability in that regard. Fig. 3 is a view in vertical 35 section of the closure to the air-discharge for releasing the pressure and setting the brakes and Fig. 4 is a top plan view of the mechanism shown in Fig. 3. Figs. 3 and 4 are on a larger scale than the other figures 40 of the drawings. Fig. 5, is a plan view on a reduced scale, of two railway tracks crossing each other and diagramming the watchman's tower and semaphores operated from 45 said tower in the usual manner and with my invention added thereto.

Like characters of reference indicate like parts throughout the several views of the drawings.

Extending from the main air reservoir 50 (not shown) of the locomotive engine 6, is the pipe 7, from which the train pipe hose 8 leads to the air brakes on the cars (not shown) in the usual manner. Connecting with this air system, here shown as by connection with the pipe 7, and terminating

above the roof of the cab, is a pipe 9 which terminates with an enlarged seat 10 for a valve-plate 11; and in order to positively seat the valve-plate and hold it from displacement by the pressure of the air in the pipes, I provide a lid 12, which is hinged to the seat 10 at 13, and has a diametrically opposite arm 14, which is preferably slightly channeled to provide a shallow seat for a holding member, here shown as cylindrical 60 pin-extension 15, from an arm 16, at right angles with and a part of a rock-shaft 17, mounted in suitable bearings 20, 20, supported by the top of the cab. A similar arm 16' extends up from the opposite end of 70 shaft 17, and when the valve is in its closed position the arms 16 and 16' stand vertically, and the pin-extension 15 is above the arm 14 of the lid in the seat formed in said arm to receive it. A set-screw 18 passes through 75 a suitably screw-threaded hole in the lid 12, into contact with the plate 11, in the manner clearly shown in Fig. 3, and when tightened forces the arm 14 against the pin 15 and the valve-plate into its seat. Considerable 80 force is then required to rock the shaft 17 sufficiently to swing the pin 15 out of engagement with arm 14, and such force is secured by providing an arm 21 at the usual 85 semaphore mast of the railway signaling system, which will be dropped down in the path of one or the other of the arms 16 or 16', depending upon which side of the engine the particular semaphore mast may be located, when the danger light or signal is to 90 be displayed.

This mast-arm 21 has an inner short arm which is connected by rod 23 with a bell-crank lever 24 at the foot of the mast, and lever 24 is connected with the usual manually operated signal-setting mechanism at a central tower 25 in the usual manner. Secured to the arm 21 is a plate 28 which operates with red and green lights 29 and 30, respectively, to cover the red light and 100 display the green one when the arm is raised, and to cover the green light and display the red one when the arm is lowered.

In the operation of my invention the exhaust of the brake-setting air to atmosphere 105 is prevented, except when the engineer disobeys a signal, by the plate 11 being seated in seat 10, and there held by the mechanism above described, in which the arms 16 and 16' of the rock-shaft 17 are vertical. 110

When the danger signal at the semaphore is set by the tower-man the arm 21 is in a lowered and horizontal position across the path of one or the other of said vertical 5 arms. But if the engineer obeys the signal and stops the train properly the signals are changed for him and arm 21 is raised to the oblique position shown by the dotted lines in Fig. 2, which allows the trip-arms 10 16 and 16' to pass without striking said semaphore arm. But should the engineer fail to heed the towerman's signal the arm 21 is contacted by one or the other of arms 16 or 16' and the brakes are set and the 15 train is stopped, by the opening of the air valve. It is then necessary for the trainmen to reset the valve mechanism and valve trip, here shown as located above the cab, which is the most convenient place, but 20 obviously it might be located elsewhere without departing from the spirit of this invention.

While I have here shown and described the best form of my invention now known 25 to me, many modifications may be made and will occur to those skilled in the art, and I therefore do not desire to be strictly confined to the disclosure here made, but what I claim as new and wish to secure, is—

30 1. The combination with a railroad train having an air-brake system, of a valve in the air system, hinged means for holding the valve closed, a rock-shaft having one or more arms and means on the arms to hold 35 a hinged means in closed position of the valve, and trip means in the path of an arm in one of the positions of the arm to open the valve by contact with the arm.

2. The combination with a railroad train 40 having an air brake system, of an air valve in said system, means for holding the valve closed comprising a hinged member and a locking member having one or more arms, and a means adapted to be moved into the 45 path of one of the arms to contact and move the arm to release the valve.

3. The combination with a railroad train 50 having an air brake system, of an air valve in said system comprising a valve seat, a valve plate in said seat, a lid fulcrumed to the valve seat member and crossing the plate, a rock-shaft having an arm with an extension from the arm to limit the movement of the lid away from the plate, an adjustable bearing between the lid and plate to force the plate into its seat, and means lo-

cated alongside the track adapted to be moved into the path of the rock-shaft arm and move it to release the valve.

4. The combination with a railroad train 60 having an air-brake system, of an air-valve in said system comprising a seat, a valve-plate in the seat, a lid hinged to the seat member and crossing the plate, a set-screw through the lid against the plate, a rock- 65 shaft having one or more arms one of which arms has an extension positioned above the lid to resist the action of the screw in separating the lid and plate, and means located beside the track to release the valve 70 by the contact of one of the arms of the rock-shaft with said means.

5. The combination with a railroad train 75 having an air-brake system, of an air-valve in said system comprising a seat, a valve-plate in the seat, a lid fulcrumed at one side to the valve-seat member and having an extension on the other side, a set-screw through the lid against the valve-plate, a rock-shaft 80 having one or more upwardly extending arms one of which arms has an extension engaging with the extension of the lid in an approximately vertical position of the arm to resist the action of the screw in separating the lid and plate, and a means 85 located beside the track adapted to be moved into the path of one of the arms of the rock-shaft to contact the latter and swing it to cause its extension to release the lid and permit the valve to open.

6. The combination with a railroad train 90 having an air brake system, of an air-pipe connected with said system, a valve seat in said pipe, a valve-plate removably seated in the valve-seat, a lid hinged at one side to the valve-seat member said lid having an arm extension on its side opposite the hinge and said arm having a depression, a set screw passing through the lid and contacting the plate, a rock-shaft mounted in bearings and having one or more upwardly extending arms one of which arms has a finger 95 which is seated in the depression of the arm of the lid, a means located beside the track and adapted to be moved into the path of one of the arms of the rock-shaft and move the arm and free the lid thereby releasing the valve-plate.

Signed at Muncie, Indiana, this the 8th day of April 1921.

GEORGE E. FRAZIER.
